UNITED STATES PATENT OFFICE

2,218,783

YIELDING SUSPENSION FOR VERTICAL
CRUSHER SHAFTSRichard Bernhard, Allentown, Pa., assignor to
Traylor Engineering and Manufacturing Com-
pany, Allentown, Pa., a corporation of Delaware

Application December 16, 1938, Serial No. 246,246

2 Claims. (Cl. 83—10)

This invention relates to vertical crushers of the type including a rotating or gyrating cone and a stationary concave between which the material is crushed, and more particularly to a yielding suspension for the crusher shaft to which the cone is secured so that the cone may settle or recede without damage to the apparatus when uncrushable substances pass into the space between the crushing members or by reason of 5 choking of the crusher by wet or sticky material.

An important object of my invention is to provide in an apparatus of the above character a yielding suspension including a plurality of cup-shaped elements associated in alternate reversed 15 relation upon the crusher shaft, these elements being composed of heavy gage spring steel and capable of limited yielding movement under heavy pressure. Such cup-shaped elements are adapted to take the place of coil springs which 20 heretofore have been commonly employed to support the crusher shaft but which require means for adjusting their tension for the heavy predetermined carrying capacity. It is difficult to obtain the necessary high yielding resistance and 25 at the same time a comparatively limited deflection with coil springs, for the head descends too far and the product is, therefore, not uniformly crushed. Furthermore, any coil spring arrangement must necessarily be bulky and so 30 located as to obstruct the feeding of the material into the crusher.

Another object of my invention is to provide a yielding suspension affording a better balance for the crusher shaft. Such improved balance is 35 attained by reason of continuous bearing contact between the circumferential edges of the companion cup-shaped elements surrounding the shaft, the circular-shaped field of bearing between companion elements being located a sub- 40 stantial distance from the axis of the crusher shaft, thus affording more stable support for the shaft. Preferably, the cup-shaped elements are enclosed within a casing adapted to be filled with a lubricant, such as oil or grease, to reduce wear 45 between the parts and prevent corrosion.

Other objects and advantages will be apparent from the following detailed description of a preferred embodiment of the invention, considered in connection with the accompanying drawing in which:

Fig. 1 is a view in vertical cross-section of the upper end of a gyratory crusher incorporating the yielding suspension of the invention; and

Fig. 2 is a perspective view of one of the cup-

shaped elements forming a part of the yielding suspension.

Referring to the drawing, Fig. 1 shows in cross-section the upper portion of a gyratory crusher which, aside from the structure constituting the 5 subject of the present invention, may be of any conventional construction, such as that disclosed in Patent No. 1,329,848 of Charles H. Patten, granted February 3, 1920. As is common to this general type of apparatus, the crusher shaft 10 carrying the cone or mantle (not shown) which cooperates with the concave (not shown) supported by the machine frame to effect the crushing of lumpy material such as stone, ore or the like, is vertically suspended at its upper end from 15 a spider 2 forming part of the machine frame. The vertically disposed crusher shaft, the upper end of which extends through a slightly tapered bore 2a in the hub 2b of the spider, is adapted to be gyrated about a fulcrum point located ad- 20 jacent the lower end of the bore by mechanism, not shown, and is supported in a manner such as to be capable of yielding in a longitudinal direc- 25 tion.

The means for yieldingly supporting the crusher shaft are as follows: Threaded upon and keyed to the upper end of the crusher shaft is a nut 3 having a cylindrical barrel portion 3a of reduced diameter extending downwardly and telescoping a short distance within a ring 4 encircling the shaft. The lower face of the ring is of concave form and this concave surface bears upon a complementary formed convex upper surface of a washer or wear plate 5, the concavo-convex bearing surface between these members being 30 developed about the fulcrum point of the shaft. The lower flat face of the washer 5 rests upon a flange 6a seated upon a shoulder 2c formed by an enlargement of the diameter of the upper end of the bore 2a. The flange 6a constitutes part of a bushing 6 which projects downwardly through the bore and provides a lining therefor. A cap 7 secured to the top of the hub 2b encloses the upper end of the crusher shaft with its associated parts.

Interposed between the nut 3 and the ring 4 and surrounding the crusher shaft are a plurality of pairs of circular cup-shaped elements 8 made of spring steel. These elements are arranged in alternate reversed relation so that companion elements of each pair of elements have continuous bearing contact at their outer circumferential edges 9 and the diameter of these cup-shaped elements is preferably such that the circular field of bearing contact between the ele- 45 50 55

ments is concentric with but spaced outwardly a substantial distance from the longitudinal axis of the crusher shaft. The individual cup-shaped elements are loosely associated with the crusher 5 shaft so as to snugly surround the same, one pair of elements resting upon an adjacent pair and contacting along a circle lying close to the circumference of the barrel portion 3a of the nut.

As best shown in Fig. 2 each cup-shaped element 8 is of solid or continuous metal construction except for the central aperture 8a through which the crusher shaft is designed to pass, and is of substantial thickness so as to resist deformation except under extremely heavy load.

15 An upwardly extending casing 10 secured to the circumferential edge of the ring 4 and enclosing the cup-shaped elements is adapted to be filled with oil or grease.

In the operation of the crusher, the shaft 1 20 is freely supported by the pairs of cup-shaped elements 8 assembled upon the upper end of the crusher between the nut 3 and the ring 4. As the shaft gyrates the spherically concave surface of ring 4 will slide upon the spherically convex 25 surface of washer 5. When an unbreakable substance, such as tramp iron, enters the crushing space between the cone and concave, or by reason of packing of this space by wet or sticky materials, the resulting component of pressure 30 along the crusher shaft causes the cup-shaped elements to flatten slightly and allow the shaft to yield in a downward direction and provide a wider space for the obstruction, which allows the tramp iron or packed material to gradually 35 discharge. The yielding support also cushions destructive shocks on the shaft, thus avoiding damage to the apparatus.

The cup-shaped elements by reason of their strength and resistance to deformation during 40 the normal operation of the crusher retain the crusher shaft in raised position with the proper amount of clearance between the cone and concave, thereby insuring uniformity of the crushed product; but when uncrushable substances are 45 encountered the cone and shaft will yield slowly without imposing undue shock upon the crusher shaft or other parts of the apparatus.

The spring suspension just described requires, no pre-compression of the yieldable elements, such as is necessary in the case of coil springs 50 in order to render them less responsive to small changes in load which occur during the normal crushing operation, but the inherent resistance of the cup-shaped elements themselves is sufficient to sustain the shaft during operation of the crusher without appreciable deformation of such elements.

Because of the balanced support for the

crusher shaft, cocking of the nut 3 with consequent injury to its threads and the threads on the shaft, is avoided. The suspension mechanism is comparatively simple and capable of being properly assembled with the crusher shaft by 5 inexperienced labor.

Instead of associating a plurality of pairs of cup-shaped elements with the crusher shaft, a single element or a single pair of elements may be sufficient in some cases. Manifestly, the invention may be embodied in other forms than that described above, which is to be regarded as exemplary rather than as restrictive of the invention.

I claim:

1. In a crusher of the gyratory type having a vertical crusher shaft carrying a cone adapted to cooperate with a concave surrounding the cone for crushing material introduced into the concave and a concavo-convex bearing encircling, supporting the crusher shaft for movement about a center of gyration located adjacent the upper end of the crusher shaft, and means providing a yielding suspension for the crusher shaft said means comprising an abutment upon the crusher shaft, a plurality of reversely arranged cup-shaped elements of spring metal completely encircling the crusher shaft and interposed intermediate the bearing and said abutment, said cup-shaped elements being 25 capable of sustaining the weight of the crusher shaft and cone without permanent distortion and capable of limited flexing to allow the shaft to yield under excessive crushing resistances.

2. The combination with a gyratory crusher 35 of the type comprising a stationary frame, a vertical shaft located within the frame, a cone carried by the shaft, a concave supported by the frame and surrounding the cone and means for imparting gyratory motion to the shaft for causing the cone to roll against and crush material in the crushing space between the cone and concave, of a pair of bearing members having complementary concavo-convex bearing faces supported within the frame and encircling the shaft 40 above the fulcrum point of the shaft, a nut secured upon the shaft and telescopically arranged with reference to one of said bearing members, and means for yieldingly supporting the shaft relative to the frame, said means comprising a 45 pair of annular cup-shaped elements of spring metal each completely encircling the shaft and interposed between the nut and the pair of bearing members, said elements being arranged in reverse relation with their circumferential edges 50 in substantially continuous bearing contact.

RICHARD BERNHARD.

CERTIFICATE OF CORRECTION.

Patent No. 2,218,783.

October 22, 1940.

RICHARD BERNHARD.

It is hereby certified that error appears in the printed specification of the above numbered patent requiring correction as follows: Page 2, second column, line 20, claim 1, for the words "concave and" read --concave,--; line 21, same claim, strike out the comma after the syllable " cling" and insert instead --and--; and that the said Letters Patent should be read with this correction therein that the same may conform to the record of the case in the Patent Office.

Signed and sealed this 19th day of November, A. D. 1940.

Henry Van Arsdale,

(Seal)

Acting Commissioner of Patents.
